JERSEY

CLIP

Application filed May 6, 1931. Serial No. 535,310.

This invention relates to an improved clip to be used on the edges of sheets or straps of material. The article is applicable for use as a paper clip and also as a clip for use on apparel such as on the slides of straps on garments such as overalls.

The object of the invention is to provide a clip that is permanently secured in place as the open clip when it has received the article 10 to be fastened and has been compressed or punched to closed position has its fastening prongs inaccessible. The prongs are so engaged by the opposite side of the clip to prevent separation of the walls or jaws of the 15 clip and hold the clip together and also hold the gripped sheet or sheets against withdrawal.

The clip of extremely simple construction 20 is of the type that can be cheaply manufactured. In addition, its manner of use is simple as it is only necessary to insert the element to be held and then firmly compress or close the clip in place.

The invention is illustrated in the accompanying drawing in which Figure 1 is a face view of a clip as applied to a slide for garments. Figure 2 is a section on line 2—2 in Figure 1. Figure 3 is a section of the clip alone in open position.

Figure 4 is a face view of a clip of modified form. Figure 5 is a section on line 5—5 in Figure 4. Figure 6 is a section of the same clip secured to the end of a strap. Figure 7 is a section of a still further modified form 35 with a strap secured in it. Figure 8 is a section of the clip shown in Figure 7 in open position.

I have elected to show the clip applied to the end of a strap 10 which is threaded 40 through a slide 11 of conventional type. The slide is used for adjusting the length of the looped part 12 of the strap which is used for suspending button loops or the like. The clip is shown dependent on a strand 13 of the 45 slide 11. The clip I illustrate is made of sheet metal bent to form opposed jaws or walls 14 and 15 connected at one end by the loop 16. The loop is placed over the strand 13 while the clip is in open position and is usually 50 closed enough to snap over the strand and

allow the use of the slide and clip as a unitary device for easy manipulation in the stamping or closing press.

The opposed jaws have co-acting means for holding the strap 10 in the clip and to hold the 55 clip against opening.

In Figures 1, 2 and 3 I show the wall 15 as punched to form a prong or prongs, 17. The opposite wall is provided with a recess 18 formed by bending back the wall 15 to form a second short wall 19. This wall 19 has a hole or holes 20 to receive the prong or prongs 17. The prongs are positioned to pass through the holes and are preferably curved or bent to facilitate their being bent easily when pressed against the wall 15 as shown in Figure 2. The open clip, as in Figure 3, is readily placed over the end of the strap 10 and then the clip is compressed or closed. The prongs 20 catch under the wall 19 and hold the walls 14 and 15 against any tendency to separate under a strong pull on strap 10 which strap is also securely held by the prongs. The prongs 70 are inaccessible and the clip is permanently in place. This device causes a large saving in material of the strap in contrast to the old practice of folding the material over the strand 13 and then stitching it.

In Figures 4, 5 and 6, I show a clip having the prongs 21 bent toward the free end of the 75 wall 15 and having the wall 19 imperforate but with its edge below the end of the prong to allow the prong to clear it. When the clip is compressed as in Figure 6 the prong is 80 caught between the wall 19 and the wall 15 85 in the recess 18 to hold the strap 10 or its equivalent and to hold the walls of the clip against any separation.

In Figures 7 and 8, I show a clip in which the wall 14 has a close return bend 22 and an 90 open return bend 23 to form the recess 24.

The return bend 22 forms a stiff retaining wall for the prong 17 of the wall 15. The prong clears the end of the bend 22 and is seated in the recess 24 when the clip is compressed as shown in Figure 7.

These clips are adapted for use in many other directions than the one illustrated and we desire to protect the clip as an article of 100

manufacture adapted for many and various uses.

We claim:

5 A clip for garment slide, comprising a sheet of metal bent into a return bend to form opposed flat walls of greater width than length one of said walls being bent again at its end to form a flat inner wall spaced from the wall from which it is bent, the said flat
10 spaced wall having spaced openings extending across its width, and spaced prongs extending inwardly from the opposed wall and arranged to pass through the openings and lie between the flat walls of the double wall
15 when the clip is compressed.

In testimony whereof they affix their signatures.

CARL E. ANDERSON.
CARL E. PETERSON.
